UNITED STATES PATENT OFFICE.

HARVEY G. SMITH, OF LOS ANGELES, CALIFORNIA.

WINDSHIELD.

1,373,840.

Specification of Letters Patent. Patented Apr. 5, 1921.

Application filed August 8, 1919. Serial No. 316,125.

To all whom it may concern:

Be it known that I, HARVEY G. SMITH, a citizen of the United States, residing at Los Angeles, in the county of Los Angeles and State of California, have invented certain new and useful Improvements in Wind-shields, of which the following is a complete specification.

My invention relates to that class of wind-shields known as auxiliary or wing wind-shields which are intended to be attached to each side of the ordinary wind-shield of a vehicle, and the object of my improvement is to provide a wind-shield which is capable of universal adjustment and to provide one which can be folded back against the main wind-shield without striking the body or door of the vehicle. Another purpose in my improvement is to provide a wind-shield which is capable of being rotated in a vertical plane and locked in that position so that a V-shaped opening is provided between the ordinary wind-shield and the wing shield thus allowing a clear vision in snow or rain storms and still reducing the draft to a minimum. I attain these objects by the mechanism illustrated in the accompanying drawings in which: Figure 1 is a plan view of my device attached to an ordinary wind-shield, the latter and also part of the attachment being shown in section. Fig. 2 is a side elevation with the clamp screws removed and the corrugations of the rotary clamp shown. Fig. 3 is an end elevation. Fig. 4 is an isometric view of the device showing slight modifications in design and with diagrammatic arrows to clearly illustrate the direction of all possible adjustments. Similar letters and figures refer to similar parts in the several views. A is the frame and G the glass of the ordinary wind-shield. 1 and 2 are the separate members of an adjustable bracket adapted to be clamped to the frame A by the screws 3. Integral with the member 2 and at right-angles to its axis is a circular bracket 4 having on its outer face the corrugations 5 and being also provided with a raised boss 6 adapted to engage with a recess on the adjacent disk 7 and for the purpose of both centering same and of taking the shearing stress on same. The circular bracket or lug 4 is also provided with a tapped hole to receive the clamp screw 8. The clamp disk

7 is provided with corrugations on its inner surface which are adapted to engage with the corrugations 5 and a hole adapted to register with the raised boss 6 of the lug 4. Integral with the clamp disk 7 and extending out from it on one side is the vertical bracket 9. This bracket is provided with a hole 10 having its axis at right angles to that of the disk 7 and is also provided with split clamp-lugs 11 and a clamp-screw 12 by which the rod 13 may be adjustably clamped therein. The rod 13 is provided with screw threads at each end. Adapted to be screwed on to each end of the rod 13 are the slotted arms 14, the said arms 14 being adjusted and locked in position on the rod 13 by the lock nuts 15. If desired the arms 14 may have a plain bearing on the rod 13 instead of the tapped hole, thus allowing a swinging adjustment without changing the distance between the said arms 14. The glass auxiliary wind-shield 16 is provided with lugs 17 which may be cemented on the glass as shown, or they may be bolted to the glass through holes for the purpose. The lugs 17 have trunnion pins 18 which are adapted to fit the slots 19 in the arms 14. The ends of these trunnion pins are threaded and are provided with the clamp-nuts 20 which lock the glass and trunnion pins in both lateral and rotative position on the arms 14.

In the alternative construction shown in Fig. 4 the vertical bracket 9 is not split but is provided with a separate clamping plate 9a. In place of the rod 13 and the slotted arms 14, the rod 21 is provided, the same being bent to three sides of a rectangle. Adapted to slide and clamp on the horizontal arms of the rod 21 are the tubular brackets 22, which are provided with an offset vertical lug 23 adapted to receive the trunnion pins 18, the said pins being locked by the same clamp-nuts 20 as in the construction shown in Figs. 1, 2 and 3. If desired the tubular brackets 22 may be split or sawed through on one side so that they will be tightly clamped on the arms of the rod 21 by the action of the clamp-nuts 20.

The operation of my device is as follows: The brackets 1 and 2 are first clamped on the main wind-shield frame A, being located in any desired position and secured by tightening the screws 3. The rod 13 or the

rod 21 is then assembled in the hole 10 of the lug 9 and secured by tightening the screw 12. The glass auxiliary wind-shield 16 is then bolted or cemented in the slots of 5 the trunnion lugs 17 and the slotted arms 14 are assembled and adjusted on the rod 13 at a distance apart from each other that the trunnion pins project up through the said slots and the arms 14 are in contact with 10 the lugs 17. The lock-nuts 15 are then set up tight. A similar method of assembly is followed in case the alternate construction with the rod 21 is used. The clamp disk 7 carrying with it the glass 16, arms 14 and 15 rod 13 or 21 is then assembled on the circular bracket 4 in position over the boss 6 and secured by the clamp-nut 8.

The operation of the assembled mechanism is clearly shown in Fig. 4 in which the 20 arrow B shows the direction of rotative movement; the arrow C the vertical adjustment of the rods 13 or 21; the arrow D the horizontal swinging movement; the arrow E the lateral adjustment of the auxiliary wind-shield on the arms 14 or on the rod 21; the arrow F the rotative adjustment of the auxiliary wind-shield on the trunnion pins 18. It will be noted that my device can be applied to existing auxiliary wind- 25 shield glasses, their varying size being accommodated by the adjustments of the spacing of the arms 14 on the rod 13. Special forms of the lugs 17 may be provided for glasses which are not rectangular or are 30 otherwise different from the form shown. 35

What I claim as my invention and desire to secure by Letters Patent is:—

1. In an auxiliary wind-shield a clamp adapted to be attached to a vehicle, a pivot lug integral with said clamp, a bracket rev- 40 olubly mounted thereon, corrugations on the adjacent faces of said lug and said bracket, a rod mounted in said bracket and capable of rotative and longitudinal adjustment, means for locking said rod, slotted 45 arms adjustably mounted at the extremities of said rod, a wind-shield revolubly mounted on trunnions capable of being adjusted and locked in said slots in said arms; all substantially as shown and described. 50

2. In an auxiliary wind-shield a clamp adapted to be attached to a vehicle, a pivot lug integral with said clamp; a bracket revolubly mounted thereon, a raised boss on said pivot lug adapted to engage a recess 55 in said bracket, corrugations on the adjacent faces of said lug and bracket, a rod mounted in said bracket and capable of rotative and longitudinal adjustment, means for locking said rod, slotted arms adjustably mounted 60 at the extremities of said rod, a wind-shield revolubly mounted on trunnions capable of being adjusted and locked in said slots in said arms; all substantially as shown and described. 65
